UNITED STATES PATENT OFFICE

2,582,058

TRAY BINDER

Orville E. Nabholz, Shellsburg, Iowa, assignor to
Le Febure Corporation, Cedar Rapids, Iowa, a
corporation of Iowa

Application July 1, 1949, Serial No. 102,587

4 Claims.

(Cl. 129—16)

1

This invention relates to office filing equipment and has particular relation to the form of filing device usually known as a tray binder.

Devices of the kind here considered serve not only as a filing means for filing cards and the like, but are used more particularly as a portable platform for alphabetically or numerically classifying ledger sheets, index cards, account sheets and the like which must be frequently referred to and perhaps pulled and replaced frequently during the business day.

It is very desirable that the operator be able to move and manipulate the cards or other records, either individually or as a block, with the greatest possible ease.

These devices commonly employ a base or platform upon which a pair of compression plates for confining the ledger sheets are movably mounted. These compressor plates may be moved toward and away from each other by means of nut members engaged to the respective plates and having threaded engagement on a shaft having oppositely disposed threads.

Such devices of the prior art have a marked disadvantage that unless the compressor plates are disengaged from the nuts, they move toward and away from each other simultaneously. It may be very necessary and desirable to move one compressor plate without moving the other. This cannot be done without disengaging one or both nuts from the screw thread one way or another.

It is an important object of my invention to avoid this disadvantage of other devices of the prior art and to provide means whereby both compressor plates are engaged to their respective driving screws at all times, but in which one blade may be moved or driven without driving the other.

Another object of my invention is to provide separate screws for each of the compressor blades so that one may be replaced without necessitating replacement of the other.

Other and further features and objects of the invention will be more apparent to those skilled in the art upon a consideration of the accompanying drawings and following specifications, wherein is disclosed a single exemplary embodiment of the invention, with the understanding, however, that such changes may be made therein as fall within the scope of the appended claims, without departing from the spirit of the invention.

In said drawings:

Figure 1 is a view in perspective of a tray binder constructed according to one embodiment of my invention. The operating crank is shown suspended in front of the tray in full lines and illus-

2

trated in dotted lines on the back of the compressor plate where it may be stowed when not in use.

Figure 2 is a view in longitudinal section of the base illustrating the driving mechanism. The front portion of the view is taken along a plane passing through the screw driving the front compressor plate, while the rear portion or right hand portion of the figure illustrates the device in section as it appears in a plane taken through the screw driving the rear compressor plate.

Figure 3 is a sectional view of the driving mechanism illustrating more particularly the relation of the gears and clutch device for driving the respective screws, and

15 Figure 4 is a view in enlarged detailed sectional view of this driving mechanism and its housing.

Referring now to the drawings:

In a preferred embodiment of my invention, I employ a hollow base 10 having rounded corners and slotted at 11 to permit the ears 12 and 13 of traveling nuts 14 and 16 to project upwardly through the base.

I preferably employ a rectangular rail 17 to surround the supporting area formed by the platform 10 of the base 10.

In the structure here shown, a follower block 18 is engaged to the upper face of the ear 12 of nut 14 and the compressor plate 19 is hingedly mounted on the upper edge of this follower block 18. The holding bracket 21 may be engaged in any one of several positions to the ear 20 of follower block 18.

The ears 13 of rear traveling nut 16 have upwardly projecting brackets 22 on which the rear compression plate 23 is pivotally engaged.

In order to drive the nuts 14 and 16, I provide two screws 31 and 32 (see Figs. 3 and 4). The left hand screw 31 is threadedly engaged in the nut 14 and may be rotated by the squared end 311 or by means of the small gear 33 which is mounted on the threaded shaft. The pitch of this screw 31 is usually three times that of the screw 32.

The screw 32 has threaded engagement in the 45 rear follower nut 16 and may be rotated by means of the squared end 322 or by the spur gear 34.

In order, then, to move the front follower block and compressor plate, it is necessary only to rotate the drive spline 311 by means of the drive shaft or crank 36 which is rotated by handle 37.

Normally, rotation of the drive spline 311 will produce rotation of the gear 34 and shaft 32 through the agency of the spur gear 33, but the stub shaft 322 may be moved rearwardly so as to move the spur gear 34 out of register with the

spur gear 33. This is accomplished by placing the drive shaft 36 over the drive spline 322 and pushing this rearwardly against the action of the spring 39, whereupon the stub shaft 322 moves rearwardly partly into a recess in shaft 32 and carries the gear 34 out of engagement with gear 33. Inasmuch as the nut 16 is still in engagement with the threaded shaft 32, rotation of the spline drive 322 will cause forward or rearward movement of the nut 16 and consequently the compressor plate 23.

In operation, if it is desired to move both compressor plates at the same time, the shafts 31 and 32 may be rotated either by splined drive portions 311 or 322, but if it is desired to drive only the rear nut 16 without moving the front drive nut 14, the splined shaft 322 is engaged by the crank 36 and pushed inwardly so that the splined portion slides into the shaft 32 and this disengages the spur gear 34 from spur gear 33. In this manner the compressor plate may be moved anywhere on the platform 101. On release of the pressure on the driving spline 322, the spring 39 will cause the movable spur gear 34 to again engage the spur gear 33 so that drive of both shafts may be produced as before.

Although I have described a specific embodiment of my invention, it is apparent that modifications thereof may be made by those skilled in the art. Such modifications may be made without departing from the spirit and scope of my invention as set forth in the appended claims.

I claim as my invention:

1. In a tray binder, a base, a pair of feed screws mounted for rotation in the base and extending in parallel relation from front to rear of the base, a compressor plate and follower block threadedly engaged on one feed screw and another compressor plate and follower block having threaded engagement on the other feed screw, gear means for driving one feed screw from the other, and means for optionally disengaging the said gear means whereby the said feed screws may be selectively driven.

2. In a tray binder, a front compressor plate, a feed screw threadedly engaged therewith, a rear compressor plate, a second feed screw threadedly engaged therewith, gears on said feed screws, and means for selectively engaging or

disengaging said gears, said means including a drive handle engageable to one of said feed screws for rotation thereof and movable longitudinally relative thereto.

3. In a tray binder, a base, a pair of feed screws mounted for rotation in the base and extending in parallel relation from front to rear of the base, a compressor plate and follower block threadedly engaged on one feed screw and another compressor plate and follower block having threaded engagement on the other feed screw, gear means for driving one feed screw from the other feed screw, and means including an operating handle for optionally and slidably shifting said gear means out of engagement, the said operating handle being adapted for rotating one of said feed screws.

4. In a tray binder, a base member, a front compressor plate and a rear compressor plate mounted on the base member for longitudinal relative movement, a pair of longitudinally extending feed screws, the first of said feed screws being threadedly engaged to the front compressor plate and the second feed screw being threadedly engaged to the rear compressor plate, meshed spur gears operatively engaged to the feed screws at one end thereof, one of said spur gears being movable longitudinally relative to its feed screw for sliding disengagement from the other of said spur gears, and an operating handle engageable with the last mentioned feed screw and movable longitudinally relative thereto for optionally disengaging the movable spur gear from the other spur gear and for selectively driving the last mentioned feed screw with or without the spur gears in engagement.

ORVIE E. NABHOLZ.
